UNITED STATES PATENT OFFICE.

AMSON FURTSCH, OF NEW YORK, N. Y.

DESIGN FOR A BUTTON.

49,016.

Specification for Design.

Patented May 9, 1916.

Application filed November 13, 1915. Serial No. 61,426. Term of patent 3½ years.

To all whom it may concern:

Be it known that I, AMSON FURTSCH, a citizen of the United States, and a resident of the borough of Manhattan, city, county, and State of New York, have invented a new, original, and ornamental Design for Buttons, of which the following is a specification.

My design is represented in the accompanying drawing, in which:

Figure 1 is a plan view. Fig. 2 is a side view of a button illustrating my new design.

The design consists of the ornamental

shape shown and it is within the scope of my invention to color the button in any way desired.

I claim:

The ornamental design for a button substantially as shown and described.

In witness whereof I have hereunto set my hand at the borough of Manhattan, city and State of New York, this 23 day of Oct., 1915.

AMSON FURTSCH.

In presence of—

H. HARLEM,
ISAAC HARLEM.
